UNITED STATES PATENT OFFICE.

GABRIEL E. ROHMER, OF NEW YORK, N. Y., ASSIGNOR, BY DIRECT AND MESNE ASSIGNMENTS, TO ARTHUR VERNON ABBOTT, OF RICHMOND, VIRGINIA.

LOW-TEMPERATURE DISTILLATION RETORT.

Application filed May 13, 1925. Serial No. 30,007.

This invention pertains to new, and improved means employed in the art of regulating the internal temperature of rotary drum-shaped retorts used for the low temperature distillation of coals containing different percentages of volatile matters or of oil bearing shale.

The prime object of the invention is to provide novel and thoroughly efficient means for the low temperature distillation or carbonization of bituminous coals, said means consisting of an especially designed externally heated retort of rotary cylindrical type which is adapted to insure a uniformity of temperature inside the distillation chamber thereof.

Another object of the invention is to provide a retort forming a pair of outer cylindrical casings, and an inner pair of cylindrical casings, with a distillation chamber between each pair of casings, each pair of casings being adapted to receive between them vessels containing molten metal.

Further objects of this invention are to so construct the retort that high volatile coals will yield their most valuable by-products at relatively low distillation temperatures (between 300° C. and 600° C.); so that the amount of volatile matters contained in the resulting semi-coke can be easily controlled, thus permitting the production of coal residues containing enough volatile matters to allow their utilization as smokeless fuels, and so as to utilize the heat conducting qualities of certain metals, such as lead, tin or other low melting point non-ferrous elements by the use of flasks or vessels filled with suitable quantities of said metals, said flasks or vessels being disposed within the inner and outer pair of casings of the retort, thereby radiating the absorbed heat, and producing an easily controllable uniformity of temperature within the distillation chamber.

The foregoing and such other objects as may appear from the ensuing description are attained by the combination, arrangement, construction and location of the several parts hereinafter more fully described, illustrated in the accompanying drawings, and particularly pointed out in the claims appended hereto, it being understood that

the preferred type of retort is horizontal, but it is readily obvious that retorts having inclined or vertical drums could be evolved, and that other changes in the precise construction and minor details of my invention may be resorted to without departing from the spirit or sacrificing any of the advantages of my invention.

In the accompanying drawings forming a part of this specification it will be seen that:

Figure 1 is a longitudinal sectional elevation of my improved retort taken through the central portion thereof, and

Figure 2 is a transverse section taken in the plane of the dotted lines 2—2, Fig. 1.

In the embodiment of my invention as illustrated, it will be seen that the numeral 1 designates a concrete foundation, although any desirable material may be utilized in the construction of said foundation for the support of the refractory structure 2 at the base in which are arranged the compartments 3. In each of these compartments and above the retort the burners 4 are so disposed as to generate the heat required for the process of low temperature distillation or carbonization.

The retort 5 is drum-shaped, and composed of a plurality of cylindrical casings 6, 7, 11 and 12 forming the annular distillation chamber 8, and between said casings 6 and 11 are disposed steel flasks or vessels 9, while other steel flasks or vessels 9 are disposed between the casings 7 and 12, each of said flasks or vessels being filled with lead, hermetically sealed, and housed within the channel members 10, which are riveted to the casings 6 and 11 and 7 and 12, respectively, said casings being secured together as a rigid unit by the brackets 52.

At the discharge end of the retort is fixedly secured a tire rim 13, adapted to engage with the rollers 15 and at the opposite end of said retort is rigidly secured a gear tire rim 14, and the pinion 16 keyed to the shaft 17, and driven by the pulleys 18 and 19, for imparting the motive power required to revolve the retort.

The combustion chamber built around the retort has its walls filled in with a suitable insulating material 20, and supports an arch

50 provided at its top with exhaust outlets 21, fitted with regulators 22, and leading to the flue 23, through which the combustion gases generated by the burners is allowed 5 to escape.

Embedded at their bases in the concrete foundation are suitable buckstays 24, adapted to furnish the necessary reinforcements required by the combustion chamber, while the 10 circular asbestos flaps 51, secured to the masonry, serve as diaphragms to prevent the escape of heat and combustion gases around the periphery of the retort.

The feeding end of the retort is equipped 15 with the hopper 25, the air tight coal distributing valve 26, a screw feed conveyer 27, a driving pulley 53, and stuffing box 28, while at the discharge end, the retort is equipped with a truncated cone discharge 20 apron 29 encased within the gas chamber 30 surmounted by a series of gas or vapor outlets 31, and a stuffing box 32 adapted to render the connection between the gas chamber and the truncated discharge apron absolutely 25 air tight, a discharge air tight valve 33 being fitted at the base of the gas chamber and empties into the discharge screw conveyer 34.

A cooling cone 35 is housed within the gas 30 manifold and is disposed concentric with the longitudinal center of the retort and in turn houses the coils 36, and within said manifold is also disposed the tar drip collector 37 with the drip pipe connection 38 35 depending therefrom.

The plurality of casings entering into the construction of the retort are each formed in the shape of a truncated cone, with their largest diameters disposed at the discharge 40 end of the retort, and the casing 6 forming the outer wall of the low temperature distillation chamber, is lined with angle iron ribs 39, said ribs running throughout the length of the retort and are slightly inclined 45 inwardly along their entire lengths. To the inner wall of the low temperature distillation chamber is fixedly secured the flanged members 40, said wall being also provided with parallel longitudinal angle ribs 41 extending the full length of the retort.

The operation of my novel apparatus may be described as follows:—

The fresh coal 42 is dumped into the feed 55 hopper 25 from whence it is distributed by the air tight valve 26 to the feed screw conveyer 27 operated by the pulley 53, and when leaving the conveyer the coal falls on the outer wall 6 of the low temperature distillation chamber, which is revolving, the coal 60 being engaged and advanced by the inclined ribs 39 as it is forced to travel in a circular and longitudinal movement, so that when the point of circular gravity is reached, as the retort revolves, the coal is 65 caused to fall on the shell 7 of the low tem-

perature distillation chamber, and since the shell 7 is lined with the ribs 41 and members 40, forming compartments in which the coal is detained while still in circular motion, said compartments serving to retard the discharge movement of the coal, thereby prolonging its exposure to heat within the retort, as owing to the inclination at which the ribs 41 are secured along the outside periphery of the inner group of cylindrical casings a gradual feed of the coal is obtained, and the material is discharged through the conical discharge 29 into the air tight valve 33, thence to the discharge screw conveyer 34. During the travel 80 through the retort the coal is alternately retarded and advanced while being subjected to the distilling or desiccating action of the heat generated by the burners and radiating from the flasks or vessels containing 85 the molten lead.

The caloric power of the burners is calculated to permit a degree of heat sufficient to not only melt the lead but also to supply 90 gradually and in a most effective manner the surplus heat which is radiated from the lead flasks or vessels.

It will be perceived that all gases resulting from the low temperature distillation action are kept from contact with the outer air by means of the stuffing boxes provided at each end of the retort, and that said gases are cooled off by being forced to contact with the surface of the cooling cone extending inside the gas chamber. In this manner and by cooling the distillation gases, their 95 expansion and flow speed are reduced, and greater efficiency will be obtained by the equipment provided for the separation of tar and oils contained therein.

Having thus described my invention what I claim and desire to secure by Letters Patent is:—

1. A low temperature distillation retort, comprising a drum formed of an outer and an inner pair of revolving concentrically disposed cylindrical casings, and a plurality of lead containing flasks disposed within the casings of each pair, whereby a distillation chamber is formed between said flasks.

2. A retort of the character described, comprising a drum formed of an outer and an inner pair of revolving concentrically disposed cylindrical casings, a lead containing vessel disposed within the outer pair of said casings, and a distillation chamber formed between the pairs of casings.

3. A retort of the character described, comprising a drum formed of an outer and an inner pair of revolving concentrically disposed cylindrical casings, a plurality of vessels containing molten metal disposed within each pair of casings, and a distillation chamber formed between the pairs of casings.

4. A retort of the character described, comprising a drum formed of an outer and an inner pair of revolving concentrically disposed cylindrical casings, a plurality of removable vessels, containing molten metal disposed within both the inner and outer pair of casings, and a low temperature distillation chamber formed between the said vessels. 5
- 10 5. A retort of the character described, comprising an outer and an inner pair of revolving concentrically disposed cylindrical casings, a molten lead container disposed within each pair of casings, and a distillation chamber formed between said contain- 15 ers. 15
- 20 6. A retort of the character described, comprising an outer and an inner pair of revolving concentrically disposed cylindri- 25 cal casings, a plurality of removable containers with molten metal therein disposed within each pair of casings, and a distilla- 30 tion chamber formed between said pair of casings. 25
- 35 7. A retort of the character described, comprising an outer and an inner pair of revolving concentrically disposed cylindrical casings, each pair of casings forming a truncated cone, a plurality of vessels con- 40 taining molten metal disposed within each pair of casings, and a distillation chamber formed between said vessels. 35
- 45 8. A retort of the character described, comprising an outer and an inner pair of revolving concentrically disposed cylindrical casings, means containing molten metal disposed within each pair of casings, a dis- 50 tillation chamber formed between said pair of casings, an air tight gas receiving cham- 55 ber at the discharge end of said retort, and gas cooling means extending into said chamber. 40
- 60 9. A retort of the character described, comprising an outer and an inner pair of revolving concentrically disposed cylindrical casings, removable means containing molten lead disposed within each pair of casings, a gas chamber fitted to the discharge end of the retort, gas cooling means extend- 65 ing within the chamber, and a distillation chamber formed between said pairs of casings. 55
- 70 10. A retort of the character described, comprising an outer and an inner pair of concentrically disposed cylindrical casings, means containing molten metal disposed within each pair of casings, a distillation chamber formed between said pairs of casings, an air tight gas chamber disposed at 75 one end of the retort, a gas cooling means extending into said chamber. 60
- 80 11. A retort of the character described, comprising an outer and an inner pair of revolving concentrically disposed cylindri- 85 cal casings, means for containing molten 90
- 90 lead disposed within the outer pair of casings, a discharge apron fixed to the discharge end of said retort, an air tight gas chamber fitted to said apron, and gas cool- 95 ing means extending into said chamber. 70
12. A retort of the character described, comprising an outer and an inner pair of concentrically disposed cylindrical casings, means containing molten metal disposed within the casings of each pair, a gas chamber fixed to one end of the retort, gas cool- 100 ing means extending into said chamber, means for collecting tar within the cham- 105 ber, and a drip connected thereto. 75
13. A retort of the character described, comprising an outer and an inner pair of concentrically disposed cylindrical casings, removable means containing molten metal disposed within the inner pair of casings, a distillation chamber formed between the 110 said pairs of casings, a discharge apron fitted to one end of the retort, a gas chamber fitted to said apron, gas cooling means disposed within the gas chamber, and tar col- 115 lecting means within said gas chamber. 80
14. A retort of the character described, comprising an outer and an inner pair of concentrically disposed cylindrical casings, means containing molten metal disposed within each pair of casings, a low tempera- 120 ture coal distillation chamber formed be- 125 tween said pairs of casings, a discharge apron fitted to one end of the retort, a gas chamber communicating with the distilla- 130 tion chamber, gas cooling means disposed within the gas chamber, and tar collecting means within said gas chamber. 95
15. A retort of the character described, comprising an outer and an inner pair of concentrically disposed cylindrical casings, means containing molten lead disposed within each pair of casings, a low tempera- 135 ture distillation chamber formed between said pairs of casings, and means within said chamber for alternately advancing and re- 140 tarding the feed of the coal through said chamber. 105
16. In a retort, an outer and an inner pair of cylindrical casings, a distillation chamber disposed between the pairs of cas- 145 ings, and a removable molten metal container disposed within the outer pair of casings. 110
17. In a retort, an outer and an inner pair of concentrically disposed cylindrical casings, a distillation chamber disposed be- 150 tween the pairs of casings, and a removable molten metal container disposed within the inner pair of casings. 120
18. In a retort, an outer and an inner pair of concentrically disposed cylindrical casings, a distillation chamber disposed be- 155 tween the pairs of casings, and a removable molten metal container disposed within the casings of each pair. 125
- 130

19. In a retort, an outer and an inner pair of concentrically disposed cylindrical casings, a low temperature distillation chamber disposed between the said pairs of casings, means containing molten metal disposed within the casings of each pair, means for alternately advancing and retarding the feed of the coal through said chamber, means for feeding the coal from the chamber, gas cooling means at the discharge end of the chamber, and means for rotating said retort.

GABRIEL E. ROHMER.
